WHEEL

John A. Main, East Lansing, Mich., assignor to Motor Wheel Corporation, Lansing, Mich.

Filed May 7, 1970, Ser. No. 22,869

Term of patent 14 years

Int. Cl. D12—14

U.S. Cl. D14—30

FIG. 1

FIG. 3

FIG. 2

FIG. 1 is a front elevational view of a wheel as viewed from the outboard face of the wheel showing my new design.

FIG. 2 is a vertical sectional view taken on the line 2—2 of FIG. 1.

FIG. 3 is a fragmentary sectional view taken on the line 3—3 of FIG. 1 but greatly enlarged thereover.

The area shaded by stippling in FIGS. 1 and 2 represents a colored velvet-like surface texture which, as best seen in FIG. 3, is imparted by fibers adhered to the wheel.

I claim:

The ornamental design for a wheel, substantially as shown and described.
